UNITED STATES PATENT OFFICE

WILLIAM C. F. KRUEGER, OF DETROIT, MICHIGAN

LIQUID VENDING MACHINE

Application filed August 19, 1929. Serial No. 386,962.

The object of this invention is to provide an improved construction for a device for vending or dispensing liquids in small quantities successively.

5 A further object of the invention is to provide an improved liquid vending machine including a liquid container and means for causing a quantity of balls to be successively projected into the container for 10 the purpose of displacing successive quantities of liquid contents of the container through a spout provided therefor.

Still another object of the invention is to provide an improved liquid vending machine including a liquid container and a coin-controlled means for successively projecting one of a series of balls into the container to displace successive quantities of liquid therefrom, the vending mechanism 20 including means whereby the coin becomes a part of the operating mechanism.

A further object of the invention is to provide an improved coin-controlled liquid vending mechanism including means for 25 automatically closing the coin ingress means when the contents of the liquid container have been depleted.

A further object of the invention is to provide simple and effective means for 30 vending or dispensing small quantities of liquid from a container.

With these and other objects in view my invention consists in the construction, arrangement and combination of the various 35 parts of my device, whereby the objects contemplated are attained, as hereinafter more fully set forth, pointed out in my claim, and illustrated in the accompanying drawings, in which:

40 Figure 1 is a perspective view of the complete device.

Figure 2 is a horizontal section on an enlarged scale on the line 2—2 of Figure 1.

45 Figure 3 is a vertical section on the line 3—3 of Figure 2.

Figure 4 is a vertical section through the coin-controlled operating mechanism on the line 4—4 of Figure 2.

50 Figure 5 is a detail cross section through

the coin-controlled operating mechanism on the line 5—5 of Figure 2.

In the accompanying drawings, I have employed the numeral 10 to designate generally a cabinet or housing and this cabinet may be provided at one side with a hinged door 11 having suitable means for locking it in closed position.

55 Mounted within the cabinet 10 is a liquid containing receptacle 12. The receptacle 12 may be in the form of the ordinary glass fruit jar having a threaded neck to receive a screw cap.

60 I have provided a special cap 13 for the receptacle, which cap is formed with a tube 14 communicating therethrough and extending upwardly from its central portion. The tube 14 is open at its upper end and preferably is enlarged to provide a funnel-shaped upper end portion 15. The cap 13 is mounted on the receptacle 12 with a 65 suitable gasket 16 interposed.

70 A platform 17 is mounted horizontally across a portion of the cabinet 10 at an elevation corresponding approximately with 75 the horizontal plane of the upper end of the tube 14 when the liquid receptacle is in place in the cabinet. The platform 17 carries the operating mechanism or coin-controlled vending mechanism.

80 It is my purpose to provide a series of objects such as spheres or balls which may be contained in the upper part of the cabinet 10 and be fed successively by force of gravity to a position where they may be projected into the liquid receptacle 12 through the tube 14, by operation of the coin-controlled 85 vending mechanism.

89 In the drawing, I have illustrated a preferred means for receiving and conveying the balls 18. This means includes a tubular conveyor 19 suitably fixed in the upper part of the cabinet 10. As here shown, the tubular conveyor 19 is formed of a coiled piece of wire and the conveyor is coiled or arranged in spiral form in order to save space and yet provide the required degree of inclination to permit the balls to travel downwardly therein.

100 The lower end of the tubular conveyor 19

is arranged in a position near one margin of the platform 17 and is arranged to discharge the balls 18 successively to a shallow cup 20 carried by the platform at a point near the bell-shaped upper end of the tube 14 which leads to the liquid receptacle.

As shown in Figure 2, a shield 21 may be provided at the side of the cup 20 opposite to the mouth of the tubular conveyor 19, to prevent the balls 18 from over running the cup. The shield 21 is not shown in Figure 3 and it is to be understood that dependence may be placed upon the formation of the cup 20 for insuring the proper positioning of the balls therein.

The liquid vending mechanism includes a frame 22 mounted upon the platform 17 and members slidably mounted upon the frame for causing the balls 18 to be successively projected from the cup 20 into the liquid receptacle.

The frame 22 includes a pair of spaced parallel walls extending from one wall of the cabinet 10 toward and on opposite sides of the ball receiving cup 20. The walls of the frame 22 constitute tracks or guides for the sliding members about to be described.

A plunger is slidably mounted in the rear or outer part of the frame 22 and includes a coin receptacle 23 and a stem 24 fixed thereto and extending slidably through the adjacent wall of the cabinet 10. The stem 24 may be formed with a knob or head 25 on its outer end to receive manual pressure for operating the device.

A coin slot 26 is formed in the wall of the cabinet 10 above the plunger stem 24 and said slot communicates with a coin chute 27 which leads inwardly and downwardly at an angle to a position above the normal position of the coin receptacle 23. The slot 26 is arranged horizontally and the chute 27 is adapted to receive a coin such as 28 and deliver it to a slotted opening 29 formed transversely of the coin receptacle 23, as shown in Figure 4.

The coin receptacle 23 rests slidably on the rear portion of the platform 17 and between the rear portions of the walls of the frame 22. It is formed at its side margins with flanges or fins 30 extending through longitudinal slots 31 in the side walls of the frame 22.

The coin receptacle 23 normally is held in retracted position, in a position close to the adjacent wall of the cabinet 10, by means of springs 32. I have shown two of the springs 32, one on each side of the coin receptacle and fixed to the projecting ends 60 of the flanges 30 and at their opposite ends to the wall of the housing.

Slidably mounted in the forward or inner part of the frame 22 is a projecting member 33, which has a part adapted to engage a ball 18 resting on the cup 20 to cause the

ball to be rolled from the cup into the upper end of the tube 14.

The projecting member 33 may be relatively narrow in its forward portion, as shown in Figure 2, so that it may be slidably received between guide pins 34 projecting upwardly from the platform 17. At the rear end of this narrow portion, the projecting member is formed with a pair of shoulders 35 adapted to engage the pins 34 for limiting the forward or inward movement of the member.

The rearmost portion of the projecting member 33 is of still greater width and is provided with flanged members 36 extending through slots 37 formed in the walls of the frame 22.

It will be noted from Figure 3 that the slots 37 which form guides or tracks for the projecting member are arranged on a horizontal plane above the slots 31 which form guides or tracks for the coin receptacle 23.

It will also be noted, particularly from the showing of Figure 4, that the rear portion of the projecting member 33 is located wholly above the coin receptacle 23 so that the latter member may move freely beneath the projecting member without causing a movement of the latter.

In order to effect an inward movement of the projecting member 33 simultaneously with a movement of the plunger device and coin receptacle 23, it is necessary to place a suitable coin such as 28 in the coin slot 26 so that it will enter the transverse slot 29 and occupy the position shown in Figure 4. In this position, the coin 28 projects upwardly from the receptacle 23, across the plane of the rear end of the projector 33, and becomes a part of the operating or vending mechanism.

It will be obvious that when a coin such as 28 has been received in the coin receptacle 23, an inward movement of the receptacle, occasioned by manual pressure on the knob of the stem 24, will cause the projecting portion of the coin to engage the rear end of the projecting member 33, as indicated by dotted lines in Figure 4 and thereby cause the projecting member to travel inwardly for engagement with a ball 18 resting on the cup 20.

This movement causes the ball 18 to be projected into the liquid receptacle 12 to displace a portion of the liquid contents thereof.

The liquid so displaced is delivered through the tube 14 and through a delivery spout 38 leading laterally therefrom through an opening 39 in one wall of the cabinet 10.

It is, of course, necessary to keep the container 12 supplied with liquid to a level corresponding with the lower margin of the outlet from the tube 14 to the delivery spout 18.

38. It is obvious that when the liquid is kept at this level, a quantity of liquid will be dispensed corresponding to the size or volume of the ball 18, which is projected into the container.

When pressure on the stem of the plunger device is released, the coin receptacle 23 will be retracted toward the adjacent wall of the cabinet by means of the springs 32.

39. The plunger device is provided with means for simultaneously retracting the projecting member 33 and this means includes a hooked member 40 fixed to the forward part of the member 23 and extending forwardly into engagement with one of the shoulders such as 41 at the forward margin of the wider part of the projecting member 33.

40. It is obvious that unless a proper coin is inserted in the slot 26 and received into the coin receptacle 23, the plunger mechanism may be moved freely on the platform 17 without causing any corresponding movement of the projecting member 33 because the hooked member 40 has a loose engagement with the projecting member and does not cause a movement thereof except in a rearward direction.

41. In other words, it is necessary to have a coin such as 28 in a position to project upwardly from the plunger device into engagement with the rear end of the projecting member, in order to effect a forward movement of the latter member when pressure is applied to the knob 25.

42. The platform 17 is formed with an opening 42 to permit the coins to drop through into the lower part of the cabinet when the coin receptacle 23 has been moved forwardly far enough to cause an operative movement 43 of the projecting member 33.

44. Rearward movement of the coin receptacle 23 and of the projecting member 33 may be limited by the parts projecting through the respective slots 31 and 37 so that the parts 45 will be properly positioned for receiving the coin 28 and for causing the desired projecting operation.

46. When one of the balls 18 is displaced from the cup 20 by operation of the projecting member 33, another ball will at once assume its position upon the cup, as soon as the projecting member is withdrawn, in readiness for another operation.

47. It is obvious that the device may be constructed so as to receive any desired number of balls and that these balls may be of any desired diameter so as to displace and thereby dispense the desired quantity of liquid.

48. The balls may be of any suitable material such as glass or non-corrosive metal.

49. In order to facilitate the passage of liquid through the tube 14 and delivery spout 38, I have found it desirable to provide these 65 parts with a coating of paraffin or the like,

which will permit the liquid to flow freely along the walls.

50. In Figure 3, I have shown an automatic closing means for the coin slot 26 which may be employed if desired, to prevent the insertion of coins when the supply of liquid in the receptacle 12 has been depleted by insertion of balls 18.

51. According to this construction, the receptacle 12 is mounted on a support 43 which is 75 pivoted between its ends on a pin or bolt 44. The opposite end of the pivoted support 43 is supplied with a counterbalance weight 45, which may be adjustable longitudinally of the support if desired.

52. Downward movement of the weighted end of the pivoted support 43 is limited by a stop or bracket 46 projecting inwardly from one wall of the cabinet 10.

53. Pivoted to the weighted end of the pivoted support 43, at the point 47, is a bar 48 which projects upwardly along one wall of the cabinet 10 and has its upper end received in a slot or opening formed at the base of the coin chute 27, as shown in Figure 4.

54. The parts are so arranged that when the receptacle 12 is filled with the liquid to be dispensed, the counter-balance weight 45 will overbalance the weight of the receptacle and its contents and cause the weighted end of the pivoted support to rest on the stop member 46, as shown in Figure 3. In this position, the upper end of the bar 48 does not project within the coin chute 27 and hence causes no hindrance to the insertion of a coin to the mechanism.

55. When the weight of the receptacle 12 has been increased by the insertion of a given number of balls 18 and a consequent removal of liquid from the receptacle, the greater weight of the balls will cause the receptacle and its contents to overbalance the counter weight 45, thereby raising the bar 48 and causing its upper end to be projected within the coin chute 27 and across the slot 26. This effectively closes the slot 26 and prevents the insertion of other coins until the dispensing machine has received attention. This may be accomplished by opening the door 11, removing the receptacle 12, emptying the balls 18 therefrom and replacing them in the tubular conveyor 19, and refilling the receptacle with liquid to be dispensed.

56. In this dispensing device I have provided a simple, economical and effective means for dispensing small and uniform quantities of a liquid, the vending operation being effected by the insertion of a proper coin which becomes a part of the operating mechanism.

57. Some changes may be made in the construction and arrangement of the parts of my device without departing from the real 130.

spirit and purpose of my invention, and it is my intention to cover by my claim, any modified forms of structure or use of mechanical equivalents, which may be reasonably included within their scope.

I claim as my invention:

In a vending machine, a cabinet, a platform therein, a pair of spaced guides on said platform each formed with a longitudinal slot, a projecting member mounted between said guides and formed with guide members projecting through the slots thereof for slidably supporting the projecting member above the platform, a plunger device slidably mounted on said platform between said guides and normally freely movable beneath said projecting member, said projecting member being formed with a seat to receive a separate device whereby the latter projects into the plane of the projecting member, said projecting member being formed with a lateral projection thereon, a hooked retracting member projecting forwardly from said plunger device and loosely engaging the projection on said projecting member, and a spring for retracting the plunger device.

WILLIAM C. F. KRUEGER.
